UNITED STATES PATENT OFFICE.

HENRY SCHURR, OF PHILADELPHIA, PENNSYLVANIA.

WINDOW-SHADE CLEANER.

Application filed August 31, 1927. Serial No. 216,516.

My invention relates to window shades and more particularly to devices adapted to prevent window shades from becoming soiled.

5 It is a well known fact that dust and dirt settles upon the top of the rolled portion of a window shade and soon discolors same to the extent that it is not cleanable. Dust and dirt also settle upon the depending portion 10 of the shade and soon penetrate into the shade fabric so that it is unsightly.

The principal object of my invention is to provide a device which will protect the rolled portion of a shade and will wipe its 15 surface when being rolled or unrolled.

Another object of my invention is to so design the device that it is neat in appearance and adaptable to shades of different lengths and which has a cleaning element 20 remaining in engagement with the rolled portion of the shade regardless of its diameter.

These objects, and other advantageous ends which will appear hereinafter, I attain in the following manner, reference being had to the accompanying drawings in which

Figure 1 is a front view of an embodiment of my invention, partly broken away, showing a portion of a shade depending therefrom.

Figure 2 is a sectional view taken substantially on line 2—2 on Figure 5, but showing the shade and cleaning element in full and 35 with one end of the cleaning element broken away.

Figure 3 is a transverse sectional view taken on line 3—3 on Figure 1 but having the shade omitted therefrom, and

40 Figure 4 a similar view but showing the carrier plate partly broken away in order to expose the end support block.

Figure 5 is a cross-sectional view, taken on line 5—5 on Figure 1,

45 Figure 6 an end view of the device shown in Figure 1, and

Figure 7 a fragmentary front view of one 50 end of the device shown in Figure 1, but showing the supporting bracket in a different position.

Figure 8 is a top plan view of a different form of end bracket which is shown attached to a fragment of the rear strip.

55 Figure 9 is a cross-sectional view, as indicated by line 3—3 on Figure 1, from which

the shade and cleaning element have been omitted and showing an inside view of the bracket shown in Figure 8, a certain part being broken away.

Figure 10 is a view similar to Figure 9 but having the carrier plate omitted, and

Figure 11 an inside view of the outside bracket plate.

Referring now more in detail to the drawings, the device may be provided with a pair 65 of supporting brackets 10, which are reversible so that they may be used with the flange turned inwardly, as shown in Figures 1 to 6, or with the flange turned outwardly, as shown in Figure 7, or supplied with a pair 70 of the brackets 10^a shown in Figures 8 to 11. A block 11 is secured to the inside of each bracket 10 in any suitable manner, as by means of screws 12, and provided with a central aperture 13 and an upper aperture 75 14.

At each end of the device, a carrier plate 15 is provided with slots 16 through which spacers 17, which are slightly thicker than carrier plate 15, extend and permit the plate 80 to slide on the surface of block 11 to which it is secured by screws 18 passing through washers 19 and spacers 17 and threaded into block 11. Each carrier plate is provided at its upper edge with a slot 20, registering 85 with aperture 14 and adapted to receive the end of a rod, as will presently be described, and with a central aperture 21, registering with aperture 13 and adapted to receive the trunnion of a shade roller; the aperture 90 in one carrier plate being rectangular, as shown, for holding the trunnion 22 of the spring element of the roller against rotation, while the aperture in the carrier plate on the opposite end of my device is circular 95 to accommodate the round trunnion 23 formed on one end of all shade rollers.

Blocks 11 at either end of my device are secured to opposite ends of a top strip 24 and to a rear strip 25 preferably by means 100 of screws which extend through both the supporting bracket and block, and thus hold the carrier plates at the proper distance from one another for supporting a shade 26.

A rod 27 has its ends mounted in slots 20 and extending into recesses 14 and carries a wiping member 28 suspended on its intermediate portion. Wiping member 28 may be made of any suitable material and is 105 preferably provided with hem 29 along each 110

edge in which rods or other suitable weights 30 are disposed.

In order to give the device a finished appearance and to protect same from dust, I provide a metal shield 31 which is secured to top strip 24 in any suitable manner but preferably by bending one edge thereof into a hook-shaped part 32 which engages the under side of an offset strip 33 secured to the rear side of top strip 24, as shown in Figures 3, 4 and 5. The lower front edge of shield 31 is notched at either corner to clear end blocks 11 and is rolled to form a tube 34 whose ends abut the inner faces of the blocks so as to keep them spaced apart at this point. A rod 35 extends through tube 34 and through both end blocks and supporting brackets and has a nut 36 threaded onto each of its ends so that the end blocks may be drawn snugly against the end of tube 34.

Tube 34 is spaced from rear strip 25 so as to provide a slot 37 through which the depending portion 38 of shade 26 may pass. As shade 26 is raised and lowered, wiping member 28 will ride on its upper surface and wipe same free of the dust and dirt which has accumulated thereon when unrolled. As the shade is drawn downwardly, the rolled portion will decrease in diameter but wiping member 28 will remain in contact therewith due to its supporting rod 27 being slidably mounted in slots 20. As the shade is drawn downwardly through slot 37, which is disposed near the rear of the device, it will tend to move the shade roller toward the rear of the device and this is allowed by the sliding action of carrier plates 15 on spacers 17. As the shade is rolled up, the shade roller is free to move forwardly for accommodating the increased diameter of the rolled shade and rod 27 may move upwardly in slots 20 as the rolled shade increases in size. Access may be had to the shade or the shade replaced by removing one shade supporting bracket and sliding shield 31 from behind strip 32.

In Figures 8 to 11, I have shown a different form of construction in which the end bracket 10^a is composed principally of an outer flanged plate 40 and an inner flanged plate 41 whose flanges are disposed on either side of rear strip 25 and secured thereto in any suitable manner, as by bolts 42. A slot 43 extends downwardly from the upper edge of plate 41 and is adapted to accommodate the end of the shade trunnion and the end of rod 27 as the trunnion moves forwardly and rearwardly and as rod 27 rises and falls due to the rolling and unrolling of the shade, as previously described.

Screws 44 are secured in holes 45 formed in plate 41 and extend through slots 46 formed in a carrier plate 47 which is held

in sliding contact with plate 41 by washers 19^a which encircle screws 44. A spacer 17^a, which is slightly thicker than carrier plate 47, is disposed in each slot 46 and encircles a screw 44 so that the carrier plate is free to move forwardly and rearwardly, relatively to plate 41 and within the limits established by slots 46, but in no other direction.

A slot 48, shown as having slightly tapered sides, extends downwardly from the upper edge of carrier plate 47 and is adapted to allow the trunnion of the shade roller to move downwardly into a pocket 49. Pocket 49 in the bracket on the left hand end of the device has parallel side walls, as shown in Figure 9, which prevent the spring trunnion from rotating, and with arcuate walls in the bracket on the right hand end of the device so that the fixed trunnion on the shade roller may rotate freely, as is customary.

Instead of securing shield 31 in place in the manner shown in Figures 1 to 7, it may be provided with a tube 34^a along its lower edge which is similar to tube 34 with the exception that it extends the entire length of the shield. Tube 34^a is preferably stiffened by being rolled around a rod 50, which is of substantially the same length as shield 31, and is adapted to be sprung into notches 51 formed in both of plates 40 and 41; the shield being preferably rolled to a slightly smaller radius than the radius of the curved portions of brackets 10^a. The upper edge of shield 31 is bent downwardly and then forwardly to form a horizontally disposed hook 52, instead of the vertically disposed hook-shaped part 32, which is adapted to engage the rearwardly extending flange of an angular retaining member 53, as plainly shown in Figures 9 and 10. Retaining member 53 extends nearly the entire length of rear strip 25 and is secured to the forward face thereof in any suitable manner.

Plates 40 and 41 are notched out at 54 in order to clear hook 52 and thus permit shield 31 being removed by merely springing tube 34^a out of notches 51 and sliding it over one of the end brackets. Due to the manner in which plates 40 and 41 are secured to rear strip 25, the device is remarkably rigid and requires no bracing, such as the top strip 24 and tube 34 shown in Figures 2 to 6, and this is particularly true if the outer edges of plates 40 and 41 are bound together in any suitable manner, as by separators 55, by forming the two plates integral, or by casting the bracket in a single piece.

The device is preferably shipped completely assembled, so that, in order to install same, it is merely necessary to secure it above a window or other opening, spring tube 34^a out of notches 51, slide shield 31 over one end bracket, lift out the cleaning element, insert the shade with an unrolled portion 130

extending through slot 37, drop the cleaning element on top of the shade, and replace the shield. Thus there is provided a device which is easily installed and which gives instant and easy access to the shade and cleaning element.

While I have described my invention as taking a particular form, it will be understood that modifications may be made without departing from the spirit thereof, and hence I do not limit myself to the precise construction set forth, but consider that I am at liberty to make such changes and alterations as fairly come within the scope of the appended claims.

I claim:

1. In a shade roller housing containing a shade, means for cleaning the shade including a rod mounted in the casing, and a flexible cleansing fabric carried by the rod and engaging the upper half of the rolled portion of the shade.

2. In a shade roller housing containing a shade, means for cleaning the shade including a rod slidable vertically in the casing, a flexible cleansing fabric carried by the rod and engaging the shade, and weights in the lower edges of the cleaning element.

3. A device of the character described including a casing, a carrier plate slidably mounted on each end of the casing and provided with an aperture for supporting an end of a shade and with a vertical slot, a rod having an end mounted in each slot, a cleaning element on the rod and engaging the shade, and weights in the edges of the cleaning element.

4. A device of the character described including a frame, end pieces secured to the

frame, a shield slidable in the frame and having one edge clamped between the end pieces, means on the end pieces for supporting a shade, and a cleaning element carried by the end pieces and engaging the upper half of the rolled portion of the shade.

5. A device of the character described including a rear piece, end brackets carried by the rear piece, carrier plates slidable on the brackets and provided with notches in which they are adapted to support a shade, a rod resting on the shade and having its ends in the notches, and a cleaning element carried by the rod.

6. A device of the character described including a rear piece, a retaining member on the rear piece, end brackets carried by the rear piece, carrier plates slidable on the brackets and provided with notches in which they are adapted to support a shade, a rod resting on the shade and having its ends in the notches, a cleaning element carried by the rod, and a shield slidably interlocking with the retaining member and engaging the brackets.

7. A device of the character described including a frame, end pieces secured to the frame, a shield slidable in the frame and having one edge clamped between the end pieces, a shade supporting plate slidable on each end piece and provided with a slot, a rod having an end slidable in each slot, a fabric carried by the rod and partially encircling the shade, weights in the edges of the fabric, and reversible mounting brackets secured to the end pieces.

In testimony whereof I have signed my name to this specification.

HENRY SCHURR.
